UNITED STATES PATENT OFFICE.

WILLIAM H. MINER, OF CHICAGO, ILLINOIS, ASSIGNOR TO W. H. MINER COMPANY, OF CHICAGO, ILLINOIS, A CORPORATION OF ILLINOIS.

DRAFT-RIGGING FOR RAILWAY-CARS.

No. 795,637.

Specification of Letters Patent.

Patented July 25, 1905.

Application filed February 20, 1905. Serial No. 246,466.

To all whom it may concern:

Be it known that I, WILLIAM H. MINER, a citizen of the United States, residing in Chicago, in the county of Cook and State of Illinois, have invented a new and useful Improvement in Draft-Rigging for Railway-Cars, of which the following is a specification.

My invention relates to improvements in draft-rigging for railway-cars, and more particularly to tandem spring-draft rigging designed for use upon passenger-cars.

My invention consists in the novel construction of parts and devices and in the novel combinations of parts and devices herein shown or described.

In the accompanying drawings, forming a part of this specification, Figure 1 is a side elevation, partly in vertical section, of a draft-rigging embodying my invention. Fig. 2 is a plan view, partly in horizontal section; and Fig. 3 is an enlarged cross-section on line 3 3 of Fig. 1.

In the drawings, A A represent the draft-sills or portion of the car-frame to which the draft-rigging is attached; A', the front sill; A², a cross-sill; A³, the buffer-block; A⁴, the movable buffer-plate; A⁵, the buffer-stem; A⁶, the buffer-spring, and A⁷ the buffer cross-bar. All these parts are of any suitable or ordinary construction.

B is the coupler, B' the draw-bar, and B² the draw-bar strap or yoke secured to the rear end of the draw-bar by a pivot b.

C C' are tandem-arranged springs, D D' D² D³ the followers, and F F are the side plates or stop-castings. Each of the side plates or stop-castings F is provided with outwardly and upwardly extending brackets or arms f to fit against the vertical webs a of the draft-sills A, to which said brackets are secured by bolts or rivets f'. Each of the side plates or stop-castings F is further provided with an outwardly-projecting horizontal flange f², fitting against and beneath the lower flange a' of the draft-sill A, and also with an upwardly-projecting shoulder or flange f³, fitting against the outer edge of said flange a' of the sill A. Bolts or rivets f³ secure said outwardly-projecting flange f² to

the draft-sill A. Each of the side plates or stop-castings F is provided with an integral upper guide f⁴ for the followers, said integral guide f⁴ consisting of an inwardly-projecting flange on the side plate F. The side plates or stop-castings F are furnished each with removable guide-plates G at their lower edges, secured thereto by short or stub bolts g, extending through feet or projections f⁵ at the lower edges of the side plates or stop-castings. Each of the side plates or stop-castings F is further provided with downwardly-projecting integral brace-arms F' F' to enable the two side plates or stop-castings to be rigidly braced apart and rigidly connected together by transversely-extending brace-thimbles K and connecting-bolts K', extending between said brace-arms below the draw-bar strap or yoke B² and followers. Each of the connecting-bolts K is furnished with a head k and with a threaded nut k' and lock-key k².

By this means or construction the draft-rigging may be made very strong, durable, safe, and reliable and at the same time be mounted entirely below the draft-sills, as illustrated in the drawings and as is frequently required in practice to accommodate or adapt the draft-rigging to particular car constructions.

I claim—

In a draft-rigging, the combination with the draft-sills, draw-bar, draw-bar extension, springs and followers, of a pair of side plates or stop-castings having outwardly and upwardly projecting brackets fitting against the vertical webs of the draft-sills and outwardly-projecting flanges fitting beneath and secured to the draft-sills, and provided with integral downwardly-projecting brace-arms and brace-thimbles and connecting-bolts extending between said downwardly-projecting brace-arms of the side plates or stop-castings, substantially as specified.

WILLIAM H. MINER.
